LANTERN SLIDE HOLDER

William C. Hyde, San Diego, Calif., assignor to
 Consolidated Advertising Corp'n. Ltd., Los Angeles, Calif.

Application March 10, 1931. Serial No. 521,421

7 Claims. (Cl. 88—26)

My invention relates to frame mountings for slides such as are used extensively in motion picture machines as a medium for advertising or which are used in schools and churches for educational and other purposes.

An important object of this invention is to improve generally upon devices of this character in such a manner as to simplify the construction and cheapen the manufacture of the article, facilitate the assembling of the component parts, add to the general appearance, permit of its reuse and greatly economize in the material used and handled.

Heretofore it has been the custom in frame mounting of slides to use two or more component parts each of which are provided with an open picture or light projection area assembled in superposed relation with respect to the glass or other picture carrying medium. Said parts are usually held together with fastening clips, which when dismantled render the frame unsightly and unfit for re-use.

Each of the open picture areas thus formed entails the use and handling of surplus waste material, adds to the cost of dies, and necessitates the use of exterior fastenings.

My improved invention involves the use of but a single piece of material; a blank, cut, molded or otherwise formed, the sides composing the base frame being provided with a depending flap which is adapted to be bent over the edge portion of the slide and having a gummed surface for adherence of the same thereto, the depending flaps being mitered in such a manner that when they are assembled their abutting edges fit with exact nicety and form a secondary frame oppositely disposed to the base frame having an open picture area complementary to that of the open area, field, or background formed in the blank which is directly opposite thereto.

The base frame may be provided with a relief, recess or boundary indicator of some nature whereby when the slide is placed thereon it may be temporarily positioned until the return folds are made on all sides and the process of mounting is completed, or the surface on which a portion of the slide rests may be gummed and such surface prevent displacement of the slide until the gummed edges of the flaps are folded over on the adjacent portions of the slide in an opposed relation to the base frame, thus permitting the use of a single apertured flat piece of material.

It is quite obvious the depending flaps could be formed with a similar relief or recess, whereby

when they are folded over and applied they would prevent displacement of the slide in the frame as will be more fully hereinafter set forth, in the latter instance the relief in the base frame could be omitted.

It is to be further understood and the invention is also to be broadly interpreted that the relief in the base frame and the secondary frame depending from the base frame could be constructed with a corresponding relief so that the sum of the two reliefs would equal that of the thickness of the slide.

An important feature incorporated in the construction of the mounting is the perforating of the furrowed line from which the flaps depend from the base frame, whereby the accumulated heat from the source of illumination may find egress, thus insuring a uniform temperature of the slide throughout.

Other features, objects and advantages of the invention will hereinafter appear as the invention is disclosed, but the foregoing will serve to broadly signify the basic intent of the invention.

For the purpose of better understanding the scope of the invention, reference is made to the accompanying drawing which forms a part of this specification whereon are shown a plurality of species all of which are covered in the claims.

The figure analysis of said drawing is as follows:

Fig. 1 is a semi-perspective front elevation of a lantern slide mounting in accordance with my invention only a fragment thereof being shown.

Fig. 2 is a semi-perspective front elevation of a lantern slide mounting in accordance with my invention only a fragment of the slide being shown and that portion being a modification of the construction shown in Fig. 1.

Fig. 3 is a plan view of the frame mounting blank shown in Fig. 1 in unfolded condition.

Fig. 4 is a plan view of the frame mounting blank shown in Fig. 2 in an unfolded condition.

Fig. 5 is an enlarged section taken on line 5—5 of Fig. 1, and

Fig. 6 is an enlarged section taken on line 6—6 of Fig. 2.

In Figs. 5 and 6 the extended or unfolded position is indicated in dotted lines.

It is obvious from the views shown that in either case the left hand view could be made to correspond with the right hand view and vice versa.

It is also obvious that from the construction taught in Figs. 5 and 6, the upper left hand secondary frame could be made dependent from the

lower right hand base frame and the upper right hand secondary frame could be made dependent from the lower left hand base frame and vice versa, to obtain sub-combinations of different interpretations of the invention.

In the construction taught by the several views I construct my invention of a single blank piece of material, of suitable cardboard or molded or resilient cast material such as celluloid or the like 10 comprising a base frame consisting of integral top and bottom frame members 1 and 2 and side members 3 and forming an apertured opening or field area 4 through which the picture is exposed. This opening or field area is usually determined 15 by standard existing conditions which must be complied with.

Depending from the top, bottom and side frame members 1, 2 and 3, forming the base frame, are integrally formed flaps 5, 6, and 7, which are 20 adapted to be bent or folded over the side edges of a slide 8 to form a secondary frame as shown in Fig. 1 having an apertured opening or field area 4a complementary to the field area 4. All along the extremity of the slide or the boundary 25 thereof as seen in Fig. 2 is a furrowed line designated at the top and bottom by numerals 9 and 10 and at the side by numeral 11.

This is the bend line of the base frame from which the flaps as before indicated, depend. Said 30 flaps 5, 6 and 7 are mitered from the intersecting point of lines 9 and 11 and 10 and 11 in such a manner that when said flaps are bent in a manner taught by the construction in Fig. 5 the edges 12 and 13 and 14 and 15 will abut with exact nicety 35 to form the open picture area 4a to correspond in exact harmony with that of the open picture area 4.

The base frame composed of members 1, 2 and 3 may be formed with a partial or whole relief 40 corresponding to the thickness of the slide which is adapted to borderize the slide whereby it may be positionally held within the frame mounting while the flaps are being secured thereto.

The construction taught by Figs. 1, 3 and 5 45 may be modified to correspond with that shown in Figs. 2, 4 and 6 whereby the relief 16 is eliminated and a boundarial indication as indicated by intersecting lines 17 and 18 may be printed on the base frame to indicate the location of the slide 50 and the area bounded within these lines may be gummed to properly adhere the slide and the mounting. By inserting a thin sharp member between the two surfaces when once adhered they can be easily separated without disfigurement, 55 thereby permitting the re-use of the slide holder.

The flaps 5, 6 and 7 may also be mitered and provided with a recess 19 whereby when the flaps 20, 21 and 22 depending from the base frame composed of members 23, 24 and 25, similar to members 1, 2 and 3 are folded over the slide as taught by Figs. 2 and 4, the relief thus formed will prevent displacement of the slide within its holder.

Flaps 20, 21 and 22 may be gummed in the same manner as flaps 5, 6 and 7 whereby the secondary frame thus formed may be easily adhered to the slide or dismantled as aforesaid.

In Figs. 2, 4 and 6 it will be noted the furrowed lines 23, 24 and 25 are provided with perforations 26 where they bend, to facilitate egress of the 70 heat contacted by the slide while it is being subjected to the intense heat of illuminating rays.

That part of the slide holder which projects beyond the slide itself is provided for, for the following reasons.

75 It maintains the standard size of the entire slide-

able member which is interchangeable in machines used for lantern slide projection and lecture work. It permits an economy of glass and reduces weight in handling and shipping. It furthermore cushions the shock of a fall when the slide is dropped, so that it seldom, if ever, breaks. 80

In assembling the slide and the slide mounting, the slide 8 is placed within the relief 16 or positioned within the boundarial indications 17 and 18. The depending flaps are then each in turn folded over upon the face of the slide and adhered thereto. 85

Such a method of mounting lantern slides is simple, inexpensive and dignified. Such a mounting also permits the use of varying colors in the material used whereby different classes of slides may be readily distinguished one from the other. The color variation also enhances the appearance and adds to the attractiveness of the slide. 90

The following is claimed:

1. The combination with the slide, of a slide holder, comprising a base frame provided with a boundarial indication adapted for positioning said slide relative to said holder and a relatively narrow slide retaining flap depending from each 100 side of said frame adapted to be folded over upon the edges of said slide to form a secondary frame cover cooperating with said base frame to retain said slide therebetween.

2. A slide holder consisting of a single piece 105 of octagonal material including a base mat having a projection opening, a relatively narrow flap depending from the respective sides of said base mat foldable over thereupon, said flaps when in folded over relation forming a secondary mat, 110 the adjacent inner edges of which enclose a projection opening corresponding in area to first said opening in combination with a slide resting between said mats and being securable thereto.

3. A frame mounting for a lantern slide comprising 115 an apertured base mat provided with a mete adapted for positioning the slide with respect to its mat, there being a marginal portion extending beyond said mete, the limits of which are defined by a scored line, relatively narrow 120 mantle flaps provided with an offset ledge depending from said scored line foldable over upon said slide, said ledges abutting the edges of said slide, and the remaining portions of said flaps extend over said slides to form a secondary cover 125 mat for said slide, the adjacent inner edges of which enclose an aperture the area of which corresponds in size and position to the aperture in said base mat, and means to adhere said base mat and flaps to said slide whereby to maintain 130 the slides designated position.

4. A picture slide holder consisting of a single piece of octagon material having a projection opening a relatively narrow flap depending from each of the parallel sides forming said projection opening foldable over and adapted to overlap and hold a picture slide therebetween, said flaps thus forming a secondary frame securable to said slide and enclosing a secondary projection opening 135 corresponding in area and position to first said opening, positioning means carried by said base frame for indicating the placement of the slide thereupon in relative relation to said projection opening, there being a marginal portion sur- 140 rounding said slide terminating at a bend line from which each of said flaps are subtended, said bend line being scored with perforations to facilitate folding said flaps and to also provide 145 egress for the heat accumulated by said slide 150

from the rays of illumination to which it is subjected.

5. A lantern slide frame comprising a base mat having a projection opening and a relatively narrow flap depending from the respective sides of said frame adapted to be folded over upon a slide resting on said mat, said flaps being provided with a relief to provide a slide seat and adhered to said slide in a manner so that the 10 opening thus formed by the adjacent inner edges of said flaps is complementary to first said projection opening.

6. A picture slide holder, comprising a base member having a rectangular projection opening in combination with a transparent slide resting thereon and covering said opening and the marginal portion of said holder adjacent said opening, said holder being provided on all sides 15 with relatively narrow foldable flaps, the folding lines of which are located in outwardly spaced 20 relation to the edge portions of said slide in order to provide a slide protecting marginal portion in the holder, said flaps being provided with an off-

set ledge and adapted to be folded over upon and secured to a facial portion of said slide with said ledges abutting the edges of said slide, said flaps in their folded position having a width corresponding to that of said base member, the adjacent inner edges of said flaps enclosing an opening in size corresponding to first said opening, the edges of the two projection openings thus formed being substantially flush.

7. The combination with the slide, of a slide retaining frame comprising a one piece mat of octagon shape including an apertured base frame and relatively narrow flaps depending from the edges of said base frame foldable over upon and securable to the slide, the oblique sides of the octagon forming a miter whereby the ends of the overlapping portion of said flaps abut, and the adjacent inner edges of said flaps enclose an opening corresponding in size to the aperture in the base frame with the inner edges of both openings substantially flush.
